UNITED STATES PATENT OFFICE.

JOHN C. WESTMONT, OF SAUK CITY, WISCONSIN, ASSIGNOR TO THE WISCONSIN FARM TRACTOR COMPANY, OF SAUK CITY, WISCONSIN, A CORPORATION OF WISCONSIN.

DESIGN FOR A TRACTOR.

58,280.

Specification for Design.

Patented June 28, 1921.

Application filed November 17, 1919. Serial No. 338,775. Term of patent 14 years.

To all whom it may concern:

Be it known that I, JOHN C. WESTMONT, a citizen of the United States, residing at Sauk City, in the county of Sauk and State of Wisconsin, have invented a new, original, and ornamental Design for a Tractor, of which the following is a specification, reference being had to the accompanying drawing, which shows my tractor in side elevation.

I claim:

The ornamental design for a tractor as shown.

JOHN E. WESTMONT.
